Inventor

Thomas O'Donnell

By Clarence O'Brien

Attorney

UNITED STATES PATENT OFFICE.

THOMAS O'DONNELL, OF IRONWOOD, MICHIGAN.

SOCKET BOX.

Application filed October 15, 1926. Serial No. 141,807.

The present invention relates to a socket box and aims to provide a device whereby several electric bulb sockets may be assembled in a compact and convenient form.

5 A still further very important object of the invention lies in the provision of a device of this nature which is exceedingly simple in its construction, capable of being cheaply manufactured, easily assembled and 10 disassembled, strong and durable, efficient and reliable in use, and otherwise well-adapted to the purpose for which it is designed.

With the above and numerous other objects in view as will appear as the description proceeds, the invention resides in certain novel features of construction, and in the combination and arrangement of parts as will be hereinafter more fully described 20 and claimed.

In the drawings:

Fig. 1 is a longitudinal vertical section through the socket box,

25 Fig. 2 is a perspective view of the socket holding member thereof.

Referring to the drawing in detail, it will be seen that the box B has a lid 5 and includes a bottom 6 and walls 7. Openings 25' and 10' are provided in the lid 5 and the bottom 6 respectively for receiving bolts 26. The particular feature of novelty in this device resides in the plug supporting structure which is in the form of a block 28 having at each end a pair of laterally extending legs 29 in spaced parallelism and provided with registering openings 30 for receiving screw 31. The plugs 16 are snugly fitted into openings in the block 28 and are electrically connected together by strips 18 30 engaged with the plug by means of screws 19. In order to further secure these plugs in place there is provided a bar 32 which is adapted to have its ends disposed between the extremities of the pairs of legs 29 and 40 has openings 33 for receiving screws 31. This bar 32 also has openings 34 for receiving bolts 26. These bolts 26 not only hold the plugs supporting structure together but also hold the lid on the box and assist in 45 holding the box on any suitable support such as the dashboard of an automobile. The leads are directed through an opening 35 provided in one end wall 7 of the box.

It is thought that the construction, utility, and advantages of the invention will now 55 be clearly understood without a more detailed description thereof. The present embodiments of the invention have been disclosed in detail merely by way of examples 60 since in actual practice they attain the features of advantage enumerated as desirable in the statement of the invention and the above description. It is apparent, however, that changes in the details of construction, and in the combination and arrangement of 65 parts may be resorted to without departing from the spirit or scope of the invention as hereinafter claimed or sacrificing any of its advantages.

Having thus described my invention, 70 what I claim as new is:—

1. A device of the class described including, in combination, a box, a lid for the box, means for holding the lid on the box, a plug supporting structure in the box, said structure comprising a body block having extending from each end a lateral pair of legs in spaced parallelism and provided with registering openings, a bar having openings at 75 its ends, said bar adapted to be received at its ends between the ends of the respective pairs of legs, screws adapted to pierce the openings, plugs mounted in the block body and extending through openings in the lid.

2. A device of the class described including, in combination, a box, a lid for the box, means for holding the lid on the box, a plug supporting structure in the box, said structure comprising a body block having extending from each end a lateral pair of legs 80 in spaced parallelism and provided with registering openings, a bar having openings at its ends, said bar adapted to be received at its ends between the ends of the respective pairs of legs, screws adapted to pierce the 85 openings, plugs mounted in the block body and extending through openings in the lid, and bolts piercing registering openings in the lid, in the block body, in the bar, and in the bottom of the box structure.

3. A device of the class described including, in combination, a box, a lid for the box, means for holding the lid on the box, a plug supporting structure in the box, said structure comprising a body block having extending from each end a lateral pair of legs in 100 105

spaced parallelism and provided with registering openings, a bar having openings at its ends, said bar adapted to be received at its ends between the ends of the respective pairs of legs, screws adapted to pierce the openings, plugs mounted in the block body and extending through openings in the lid,

and bolts piercing registering openings in the lid, in the block body, in the bar, and in the bottom of the box structure, a pair of ¹⁰ strips connecting the plugs in parallel, and leads extending therefrom.

In testimony whereof I affix my signature.

THOMAS O'DONNELL.
